FOUNTAIN PEN CAP HAVING A MULTIPLE CYLINDER, SINGLE AXIS CALENDAR

Sophie Gonczi, Union City, N. J.

Application July 29, 1944, Serial No. 547,140

1 Claim. (Cl. 40—108)

1

This invention relates to new and useful improvements in a writing instrument and more particularly to a cap for a fountain pen having a multiple cylinder, single axis calendar.

More specifically, the present invention proposes the construction of a writing instrument having a built-in calendar capable of recording the day, month and year for many years.

A further object is to provide an instrument as aforesaid in which the day, month and year are recorded on interfitted cylinders so that they are adjustable by rotation.

For further comprehension of the invention, and of the objects and advantages thereof, reference will be had to the following description and accompanying drawings, and to the appended claim in which the various novel features of the invention are more particularly set forth.

In the accompanying drawings forming a material part of this disclosure—

Fig. 1 is a perspective view of a fountain pen constructed in accordance with this invention.

Fig. 2 is an enlarged central section through the fountain pen cap.

Fig. 3 is an enlarged perspective view of a lock ring of the cap.

Fig. 4 is an enlarged perspective view of the barrel of the cap.

Fig. 5 is an enlarged perspective view of the year cylinder of the cap.

Fig. 6 is an enlarged perspective view of the month cylinder of the cap.

Fig. 7 is an enlarged perspective view of the outermost day cylinder of the cap.

Fig. 8 is an enlarged perspective view of the intermediate day cylinder of the cap.

Fig. 9 is an enlarged perspective view of the innermost day cylinder of the cap.

The present invention is adapted for use with various types of writing instruments such as pencils and pens. For simplicity, it is shown applied to the cap of a fountain pen but it will be understood that it can also be applied to the body of a pencil or pen.

The fountain pen, according to this invention, comprises a pen part 10 on which is secured a cap 11 which functions like a conventional fountain pen cap to cover the pen point when the pen is not in use and is pushed on the end remote from the pen point when the pen is in use.

Cap 11 comprises a barrel 12 including a lower cylindrical portion 13 having a window 14 for viewing the days of the week as will presently appear. The names of the days are printed on the cap at one side of the window 14. The barrel

2

has an intermediate cylindrical portion 15, of larger diameter than the portion 13, provided with a window 16 for viewing the months as will presently appear. The barrel 12 also has a still larger upper cylindrical portion 17 in which is formed a window 18 for viewing the years as will presently appear, the number 19 being printed on the portion 17 at one side of the window. The top of the barrel has external threads 19 and at the bottom of the barrel is an internal threaded wall 20 spaced from the portion 13 and connected thereto.

In the barrel are disposed five thin cylinders fitting one within the other, each of the cylinders being rotatable and slideable relative to the other cylinders. The innermost cylinder 21 has a continuous uninterrupted cylindrical wall which at its upper portion has a neck 22 closed at its top by a wall 23. On this cylinder 21 are longitudinal rows of numbers representing days of the week. Each row has seven day numbers, as is clearly shown in Fig. 9, each successive row starting with one day later than the row before.

The next cylinder 24 is similar to the cylinder 21 except that it is larger so that cylinder 21 fits inside of it with a sliding fit, and it is provided with a longitudinal window 25 through which the numbers of cylinder 21 may be viewed when the cylinders are properly adjusted for this. The top of the neck 26 of cylinder 24 is open, and neck 22 extends therethrough.

The next cylinder 27 is similar to cylinder 24 but is larger so that cylinder 24 can fit within it, with its neck extending through the open end of the neck 28 of cylinder 27. Cylinder 27 is provided with a window 29 through which the numbers of cylinder 24 may be viewed. The outside diameter of cylinder 27 is slightly less than the inside diameter of portion 13 of barrel 12 so that it can rotate therein.

A cylinder 30 is mounted on cylinder 27, neck 28 extending through the open neck 31 of cylinder 30. The names of the months are printed on cylinder 30, this cylinder being disposed with its lower portion in the barrel portion 15.

A cylinder 32 is mounted on cylinder 30, neck 31 extending through the open neck 33 of cylinder 32. The last two members of successive years are printed on the cylinder 32. This cylinder is disposed in the portion 17 of the barrel.

A lock ring 34 having a central orifice 35 through which neck 33 extends, is screwed on the top of the barrel.

The operation of the device is as follows: The lock ring 34 is loosened and neck 33 is

seized in a person's fingers and cylinder 32 is rotated thereby until the current year numbers show through window 18. The neck 31 is then seized and cylinder 30 rotated until the current month shows through the window 16, neck 33 being held stationary by the fingers of the other hand during rotation of the cylinder 30. The neck 28 is then seized and cylinder 27 rotated until the current row of day numbers shows through the window 14. Necks 31 and 33 are held stationary during rotation of cylinder 27.

If the current row of day numbers is not on cylinder 27, the window 29 is lined up with window 14 and neck 26 is seized and cylinder 24 rotated. If the current row of day numbers is not on cylinder 24, the window 25 is lined up with windows 29 and 14 and neck 23 is seized and cylinder 21 rotated until the current row of day numbers is visible.

The lock ring 34 is then rotated to screw it firmly on the barrel, the lock ring pressing downward on the portion of the cylinders surrounding their necks, thereby holding all of the cylinders in their proper adjusted position.

Each of the necks is serrated at its top to provide a finger hold. It will be noted by reference to Fig. 1 that the protruding necks make a very attractive top ornament for the fountain pen cap. It is contemplated that each of the cylinders will be made of thin metal such as hard brass which slides easily and is strong. The construction of the cylinders having two cylindrical portions connected by an annular portion provides a very strong structure able to withstand much rotating. While three day number cylinders have been shown, providing ample space for the numbers of rows of numbers needed to show the days of the month a week at a time, more or less day number cylinders may be employed if desired.

The internally threaded wall 20 provides means for retaining the bottom of the day number cylinders and also for screwing on the part 10. It is a feature of the present invention that the innermost day number cylinder provide the inside wall of the cap. The names and numbers may be printed on the cylinders in any desired manner, but they are preferably first etched so that they will not wear off due to rotation of the cylinders.

While I have illustrated and described the preferred embodiments of my invention, it is to be understood that I do not limit myself to the precise constructions herein disclosed and the right is reserved to all changes and modifications coming within the scope of the invention as defined in the appended claim.

Having thus described my invention, what I claim as new and desire to secure by United States Letters Patent is:

A fountain pen cap comprising a cylindrical barrel having at its bottom, an inner short wall interiorly threaded, a lower cylindrical portion spaced from said short wall, a bottom wall connecting said walls, the upper portion of said barrel being stepped twice providing an upper cylindrical portion and an intermediate cylindrical portion, the upper cylindrical portion of said barrel being exteriorly threaded, said upper cylindrical portion having a small window, said intermediate cylindrical portion having a small window, a longitudinal window in said lower cylindrical portion, the latter having the days of the week indicia thereon along one side of said 10 longitudinal window and the first two numbers of the year indicia along one side of the window in said upper cylindrical portion, three interfitting cylinders disposed in said cylindrical barrel with their lower ends disposed on said bottom wall, each of said cylinders having a neck at its upper end, the innermost cylinder neck extending through and beyond the intermediate cylinder neck and the intermediate cylinder neck extending through and beyond the outer cylinder neck, 15 20 25 30 35 40 45 50 55 60 said outer cylinder neck extending above said barrel, said intermediate and outer cylinders each having a longitudinal window and said three cylinders having indicia of the days of the month, two additional cylinders, one of said cylinders being disposed within said intermediate cylindrical portion and having a neck surrounding and shorter than said outer cylinder neck, months of the year indicia on the said one cylinder, the other of said cylinders being disposed within said upper cylindrical portion and having a neck surrounding and shorter than the neck of the first of said additional cylinders, the second two numbers of a series of years indicia on said other cylinder, and a retaining ring surrounding said other cylinder neck and upper cylindrical portion and screwed on the exterior threads of said upper cylindrical portion for retaining all of the aforesaid parts of said cap together.
